UNITED STATES PATENT OFFICE

CHARLES NELSON POGUE, OF WINNIPEG, MANITOBA, CANADA, ASSIGNOR TO ALFRED JOSEPH ANDREWS, OF WINNIPEG, CANADA

MEANS FOR FORMING COMBUSTIBLE MIXTURES

Application filed December 1, 1927. Serial No. 237,101.

This invention relates to improvements in means for forming combustible mixtures and particularly combustible mixtures adapted to be used in internal combustion engines and the objects of the invention are to effect an economy in the use of combustible fuel such as gasoline.

A further object of the invention is to utilize the gasoline tank as a source of supply for the combustion vapours which in accordance with my invention are introduced into an internal combustion engine through the medium of a carburetor. A further object of the invention is to provide a means of forming a combustible mixture in the gasoline tank to co-operate with the car and increase the efficiency of the engine.

The invention in the main consists essentially of a gasoline tank having a conducting conduit connected thereto, one end of which leads from a warm air chamber connected to the exhaust manifold while a second conduit is connected to a fuel tank and leads to the intake of the carburetor. Means are also associated with the invention whereby air is introduced into the gasoline tank to provide a form of vaporization within the tank and, in addition to this, agitating means conveniently operated are provided which is designed to provide further means of vaporizing the combustible fluid within the tank which, as will be hereinafter explained, is directed to the engine for consumption.

In the accompanying drawings in which like characters of reference indicate corresponding parts,

Figure 1 is a side elevation partly in section showing the embodiment of my invention.

Figure 2 is a plan view of my improved device as associated with a motor car.

Figure 3 is an enlarged transverse section of the fuel or gasoline tank illustrating the agitating means therein.

Figure 4 is a detailed section illustrating the mechanism by which the agitator is operated within the fuel tank.

Figure 5 is a sectional detail of the air line connected with the carburetor and illustrating the back-firing valve therein.

Referring now particularly to the drawings in which my improved device is illustrated, A indicates an automobile of any well known type, B the engine thereof, C the carburetor and D the fuel or gasoline tank. The tank may be of any convenient form and, in accordance with the present invention, one side thereof is connected by a flexible conduit 10 with the air intake 11 of the carburetor C. The opposite side thereof, as will be seen by referring to Figure 2, has connected thereto a flexible conduit 12 leading from a hot air chamber 13 which surrounds the exhaust manifold 14 of the engine B.

In this particular type of invention it is essential that means be provided whereby the fuel within the tank is agitated in such a manner as to create vapors or fumes which, as will be hereinafter more fully explained, is directed to the carburetor for consumption in the engine. The means as shown in the present invention is an agitator comprising a float 15 provided with wings 16 vertically slidable and rotatably mounted upon a square or hexagonal shaft 17.

On reference to Figure 3 it will be seen that the shaft 17 extends upwardly into a housing 18 and is provided at the top with a bevel gear 19 meshing with a bevel gear 20 which in turn is mounted on a shaft 21. The shaft 21 in turn is connected through a length of flexible shafting 22 to the shaft 23 which is mounted in the exhaust manifold 14 and is provided with a series of propeller blades 24.

The operation of the agitating member 15 will at once become apparent. The spent gas travelling through the exhaust manifold will rotate the blades 24 upon the shaft 23 in turn operating the shaft 17 to cause the agitator with wings 16 thereon to agitate the fuel within the tank D. Particular provision is made in this case in that the member 15 is formed of cork or other light material whereby this member always remains at the level of the fuel within the tank.

In addition to the foregoing, a further means of agitating the fuel in the tank comprise the introduction of air thereinto, pref-

erably from the base hereof. The means which I have shown comprise an air line 25 connected to any convenient type of air compressor 26 which may be driven through the 5 operation of the engine B and connected to the base of the tank D as indicated at 27. A valve 28 within the tank is provided with a ball check 29 by which means air is permitted to enter therein while preventing the fuel 10 from entering the air line 25.

Within the tank D I provide baffle plates 30 designed to prevent excessive splashing of fuel within the tank.

The air intake 11, previously referred to 15 and as particularly illustrated in Figure 5, is provided with a back-firing valve 31 and a flap valve 32. The valve 31 is designed to permit the vaporized fuel to pass from the tank to the carburetor but in the event of 20 back-firing through the carburetor the valve will prevent the back-fire from entering the gasoline tank. As the valve 31 closes to prevent the back-fire from entering the gasoline tank, the flap valve 32 automatically 25 opens and allows the back-fire to escape to the atmosphere.

In operation the action of the engine will cause air to be forced into the fuel tank by the operation of the pump 26 which will agitate and tend to vaporize the fuel. Simultaneously with this operation the spent gases of exhaustion will operate the blades on the shaft 23 which in turn will affect the operation of the agitator member 15 which through 30 its rotary movement will create a vapour within the fuel tank. The suction of the engine operating through the carburetor and the intake thereof will simultaneously with the aforementioned operation create a suction in the conduit 10 which will draw off the fuel vapours or fumes from the upper part of the tank D which have been created therein. During this operation heated air passes from 35 the hot air chamber associated with the exhaust manifold by means of the conduit 12 to the tank D which will further assist in the vaporization of the fuel within the tank.

From the foregoing it will be apparent that 40 novel and effective means are provided for the creating of vapours or fumes within the fuel tank for consumption by the engine.

As many changes could be made in the 45 above construction and many apparently widely different embodiments of my invention, within the scope of the claims, constructed without departing from the spirit or scope thereof, it is intended that all matter contained in the accompanying specification and drawings shall be interpreted as 50 illustrative and not in a limiting sense.

What I claim as my invention is:—

1. A device for the formation of combustible mixtures comprising in combination, an intake manifold, an air pump, an exhaust 55 manifold, and a fuel tank, a conducting con-

duit connecting the fuel tank with the intake manifold, a warm air chamber surrounding the exhaust manifold, a secondary conduit connecting the warm air chamber with the fuel tank, an agitator within the fuel tank, 70 an air conducting conduit connecting the air pump with the fuel tank and adapted to supply air thereto, and means associated with the exhaust manifold adapted to operate the agitator within the tank.

2. An apparatus of the character described for forming combustible mixtures comprising in combination, an intake manifold, an exhaust manifold, a fuel tank, a heating chamber, and an agitator, means associated with the exhaust manifold adapted to operate the agitator, a conducting conduit connecting the heating chamber with the fuel tank and a conducting conduit connecting the fuel tank with the intake manifold adapted to conduct 85 a vaporized fuel which has been created by the agitator to the carburetor.

3. A device as claimed in claim 2 in which the agitator comprises a float member provided with a plurality of agitating wings.

4. A device as claimed in claim 1 in which the agitating means are substantially in the form of a rotatable float capable of vertical movement thereby causing the agitating member to maintain its relative position with regard to the surface level of the fuel within the tank.

5. A device as claimed in claim 1 in which valve means are provided in the air conducting conduit adapted to permit the entrance of air into the tank while retaining the fuel therein.

6. A device as claimed in claim 2 in which the drive mechanism adapted to operate the agitator member comprises a shaft in the exhaust manifold provided with a series of blades operatively connected to the agitating member.

In witness whereof I have hereunto set my hand.

CHARLES NELSON POGUE.
